INFLATABLE WALLED STRUCTURE

Victor H. Hasselquist, Akron, Ohio, assignor to
The B. F. Goodrich Company, New York, N. Y.,
a corporation of New York

Application April 1, 1950, Serial No. 153,415

10 Claims. (Cl. 135—1)

1 This invention relates to walled structures of limp, pliable, impervious material and to the closing of inflatable walled structures, and is especially useful in the construction of tents, canopies, boats, and the like, although features of the invention are useful also in the construction of other walled structures.

Limp, pliable, sheet material such as polymerized vinyl chloride compositions is resistant to the effects of sunlight and is waterproof and has been found desirable for use in the construction of tents and other walled structures exposed to the weather. Such structures have usually required supporting frames of stiff material which have added considerable weight and bulk to the structure and have involved difficulties in transportation of the structure.

In my application, Serial No. 74,033, filed February 1, 1949, and entitled "Wall Structure," I have disclosed a walled structure consisting of pliable impervious sheet material in superimposed sheets united along their margins and along lines intermediate their margins to provide a series of pockets which can be inflated to stiffen the wall thereby providing an enclosure without the necessity of a supporting frame of stiff material.

The present invention is directed to improvements useful in walled structures such for example as disclosed in my aforesaid application, and especially to the means for inflating the inflatable pockets and for sealing off such pockets from the atmosphere.

Objects of the invention are to provide for facility of inflation of a walled structure; to provide for superior sealing of the pockets and to facilitate manufacture.

These and other objects will appear from the following description and the accompanying drawings.

Of the drawings,

Fig. 1 is a perspective view of a walled structure constructed in accordance with and embodying the invention, the structure being in the form of a tent of conical form.

Fig. 2 is a developed plan view of the walled structure of the tent of Fig. 1 in uninflated condition.

Fig. 3 is an enlarged view of the apex portion of the tent as seen in Fig. 2, other parts being broken away.

Fig. 4 is a vertical sectional view of the apex of the tent in its inflated condition showing the clamping means in use.

Fig. 5 is a sectional view of the inner backing ring.

2 Fig. 6 is a perspective view illustrating the placing of the inflated wall structure about the inner backing ring.

Fig. 7 is a similar view showing the step of rolling the resilient clamping ring into clamping and sealing position.

Referring to the drawings, and first to Fig. 1, this shows a walled structure 10 of generally conical form and resembling the tepees used by the American Indians, the wall member of this structure, as will be seen from Figs. 1 and 2, comprising a series of inflatable pockets 11, each of generally conical shape, the pockets being secured to each other side by side with the small ends 15 11a of the pockets at or near the center of an arcuate margin 9 formed by the bases of the pockets.

Conveniently, such a wall member may be formed by superimposing two sheets of pliable impervious material such as polymerized vinyl chloride composition, the sheets being of approximately semi-circular shape, and uniting the sheets about their margins and also along lines corresponding to radii of the arc defining the curved margins of the sheets and arranged at regularly spaced intervals throughout the extent of the arc, thereby providing pockets therebetween. The sheets of material are left unadhered to each other over an area adjacent the small ends of the pockets so that the pockets communicate with this space which provides a manifold 8 extending along the short upper margin of the conical wall. A tubular tab or extension 12 is provided at one end of the manifold 8 and is connected thereto in communication therewith to provide means for inflating the manifold and the connecting pockets. The opposite end of the manifold is sealed off as by a seam 13 extending thereacross, but a tab 14 is provided beyond the seamed portion for ease of manipulation in applying the clamping means.

Inflation may be accomplished by inserting a hollow tube such as a lemonade straw, or rubber tubing, in the opening at the end of the tab 12 and by blowing through the tube the manifold and the pockets connected therewith may be inflated to the desired amount. The tab 12 may then be pinched between the fingers to prevent loss of air until the clamping means is applied.

For sealing off the inflated pockets, a ring 16 of metal or other material, preferably of a stiff nature, and generally of frusto-conical or domed form is provided for supporting the upper margin 55 of the wall member, the upper margin of the

walled member being wrapped thereabout, as illustrated in Fig. 6, where the tab 12 is held against the outer surface of the ring while the margin is drawn about the ring and the tab 14, held by the other hand, is then lapped over the tab 12. For retaining the wall member in place on the backing or supporting ring and at the same time sealing off communication from the inflated pockets, clamping member, preferably resilient annular ring 17, of rubber or similar material is placed over the margin of the wall member and resiliently presses against the wall member at the entrances to the pockets, sealing off the pockets from each other. The ring 16 is provided with two circumferential grooves, which provide for increased convenience of application of the clamp. One groove 18 is near the small end of the conical ring and is employed for normally supporting the resilient ring 17 when the supporting ring is detached from the wall members. The other groove 19 is near the large end of the stiff ring and is used to seat the resilient clamping ring in clamping position. The grooves 18 and 19 are separated by a rounded hump 25 in the ring 16, as shown, over which the elastic ring may be rolled from one groove to the other. With the supporting ring detached from the wall member, and with the resilient ring initially in the groove 18, the wall member may be wrapped about the ring as illustrated in Fig. 6, the upper margin of the wall being laid close to the resilient ring 17 with the wall member wrapped about the supporting ring. The resilient clamping ring 17 is then rolled from its groove 18 down over the large end of the supporting ring and the upper margin of the wall member is wrapped thereabout and held by the hands until ring 17 snaps into the groove 19 in the lower end of the supporting ring, in which position the ring 17 overlies the small ends of all the pockets, thereby sealing each pocket from the manifold and from the other pockets so that should puncture of one of the pockets take place the other pockets will remain inflated.

If desired, the supporting ring 16 may be provided with openings 20 for receiving feathers or other suitable ornaments. Also the sloping margins at the entrance to the tent may be formed with fringe 21, 22 therealong for ornamental purposes. Apertured tabs 23 may be provided at the lower margin of the wall member whereby stakes may be driven through the apertures 24 to prevent overturning of the structure by wind. These tabs may be constructed of the sheet material of the wall member or may be made separately and cemented, seamed or otherwise secured thereto.

While a tent of conical shape has been shown in the drawings, features of the invention will be found useful also in connection with walled structures of cylindrical and other shapes.

Variations may be made without departing from the scope of the invention as it is defined by the following claims.

I claim:

1. An inflatable walled structure having a wall comprising pliable material providing a plurality of inflatable pockets each having an inflation entrance, means connecting said inflation entrances for simultaneous inflation, a backing for said pockets adjacent said entrances, and means for clamping said pockets upon said backing to seal said pockets collectively, the clamping means comprising resilient material for disposition across said pockets adjacent said entrances

to apply the clamping pressure resiliently against said pockets as a group.

2. An inflatable walled structure having a wall comprising pliable material providing a plurality of inflatable pockets each having an inflation entrance, means connecting said inflation entrances for simultaneous inflation, a backing for said pockets adjacent said entrances, and means for clamping said pockets upon said backing to seal said pockets collectively, the clamping means comprising an elastic ring of resilient material for tensioning across said pockets adjacent said entrances to apply the clamping pressure resiliently against said pockets as a group.

3. An inflatable walled structure having a wall comprising pliable material providing a plurality of inflatable pockets each having an inflation entrance, means connecting said inflation entrances for simultaneous inflation, an annular member for backing said pockets adjacent said entrances, and clamping means comprising resilient material in annular form for resiliently embracing the backing member and said pockets in the region of their entrances to seal said pockets collectively.

4. A walled structure having a wall comprising pliable material providing a plurality of inflatable pockets terminating at a margin of said wall, means at said margin for inflating said pockets, an annular member for backing said wall along said margin, and an elastic clamping ring for embracing said member and said margin resiliently to close said inflatable pockets as a group.

5. A walled structure having a wall comprising pliable material enclosing a plurality of inflatable pockets terminating at a margin of said wall, means at said margin for inflating said pockets, an annular member for backing said wall along said margin, said annular member being of generally frusto-conical shape and having a ring-seating groove at its small end for supporting a clamping ring while said wall is on said annular member adjacent thereto and having a second ring-seating groove of larger circumference underlying said wall, and a clamping ring of resilient material for seating in the first said groove, said clamping ring being movable over the margin of said wall by rolling it thereover to seat in the second said groove to close said pockets.

6. A substantially conical walled structure having a wall comprising pliable material enclosing a plurality of elongate pockets and a manifold connecting the pockets at the apex of the walled structure for inflation of the pockets, said manifold terminating in an inflation aperture remote from said pockets, and clamping means for closing said pockets from communication with said manifold, said clamping means comprising an annular member for backing said wall along said manifold and a resilient clamping ring for constricting said wall structure upon the backing member.

7. A walled structure having a wall comprising pliable material enclosing a multiplicity of inflatable pockets terminating at one margin of said wall in a manifold along said margin, said manifold having an inflation opening at a margin of said wall, an annular member for supporting said wall along said manifold when the margin of said wall is wrapped thereabout, and a resilient ring for resiliently embracing said wrapped margin upon said member and sealing off communication between said pockets and said manifold.

75 8. Means for sealing a pocketed inflatable wall

structure having a group of inflatable pockets, said means comprising an annular member for backing said pockets across the same, said member being generally of frusto-conical shape and peripherally grooved near its larger and smaller ends and adapted to receive said wall structure against the exterior surface thereof, and annular clamping means comprising a ring of resilient material around said member and adapted for disposition across said pockets for pressing said 10 pockets upon said member to seal said pockets collectively, said resilient element being normally seated in the groove at the smaller end of said annular member beyond said inflatable wall structure and being positionable in the groove 15 at the larger end of the annular member in its sealing position by rolling movement of said ring along said member over said wall structure.

9. Means for sealing a pocketed inflatable wall structure having a group of inflatable pockets, said means comprising an annular member for backing said pockets across the same, said member having a peripheral surface adapted to receive said wall structure thereagainst, the surface being larger in circumference at one annular margin thereof than at the opposite annular margin and having peripheral grooves at said 25 margins separated by a bulged intermediate annular portion, and a resilient clamping ring normally disposed in the smaller of said peripheral 30 grooves and adapted by rolling movement for disposition across said pockets adjacent said member when the wall structure is disposed against said surface for pressing said pockets upon said member to seal said pockets collectively, said re- 35

silent ring being shiftable from one of said grooves to the other by rolling said ring over the bulged intermediate portion of said member.

10. A sealing device for an inflatable margin 5 of a flexible-walled article, the device comprising a member having an exterior surface in the shape of a surface of revolution with respect to a central longitudinal axis through the member, which surface is adapted to receive the inflatable margin of the article, the surface including a pair of spaced-apart annular grooves therein one of which has a greater circumference than the other groove, and an endless elastic ring of circular cross sectional shape stretched in tension around said member and engageable with the grooves, the ring being rollable from the groove of smaller circumference to the other groove across the surface intermediate the grooves to vary the tension in the ring and to effect engagement of the 20 margin in the groove of greater circumference when the margin is disposed on said surface.

VICTOR H. HASSELQUIST.
